UNITED STATES PATENT OFFICE

ANDREW M. LOCKETT, OF NEW ORLEANS, LOUISIANA, ASSIGNOR TO A. M. LOCKETT & COMPANY, LTD., OF NEW ORLEANS, LOUISIANA, A CORPORATION OF LOUISIANA

DREDGE

Application filed June 8, 1929. Serial No. 369,484.

This invention relates to dredges or excavating machines, and particularly has to do with hydraulic dredges utilized in handling sand and gravel or other similar material.

5 The principal object of the invention is to produce a simple, efficient and durable machine which will rapidly and effectively remove the material being handled from the bed or deposit and convey the same to a point 10 of discharge.

Another object of the invention is the provision of a device of this character in which all bearings are fully protected and are not exposed in any way to the material being 15 dredged or excavated, and wherein the drive of the excavating element is confined within a bath of lubricating material.

Further objects of the invention will be apparent from a reading of the following 20 specific description, when taken in connection with the accompanying drawings which form a part of this application:

In the proposed construction of my device I employ a fluid motor which serves not only 25 to actuate the excavating element or elements but in which the water utilized for driving the motor may be subsequently employed for discharging the excavated material. In doing this, the parts have been so arranged that 30 the drive between the motor and the excavating elements is not exposed to the abrasive action of the material being excavated and the shaft which drives the excavating element is only exposed to clean fluid thereby 35 avoiding the usual wear encountered in the operation of similar devices.

The invention consists of structural characteristics and relative arrangement of elements, which will be hereinafter more fully 40 described and particularly pointed out in the appended claims.

In the two sheets of drawings, in which similar reference characters indicate the same parts in the several figures of the drawings, 45 Figure 1 is a side elevation of the apparatus;

Figure 2 is a fragmentary vertical sectional view taken on line II-II of Figure 4;

50 Figure 3 is a vertical sectional view taken on line III-III of Figure 4;

Figure 4 is a horizontal sectional view taken on line IV-IV of Figure 1;

Figure 5 is a vertical sectional view taken through the motor on line V-V of Figure 1;

Figure 6 is a fragmentary side elevation of 55 the discharge pipe provided with a valve.

Figures 7 and 8 are front and side elevations, respectively, of a modified form of means for removing obstructions from the interior of the dredge and operating the 60 dredge; and,

Figures 9 and 10 are side elevation and fragmentary plan views of a further modified form for same purpose as Figures 6 and 7.

Referring more particularly to Figures 1 65 and 2 of the drawings, I have shown an elongated casing generally indicated at 10 which is divided into three different sections, 10^a, 10^b, and 10^c. The section 10^a, as shown, is provided with a flange 11 at its lower end which corresponds with a flange 12 on the upper end of the section 10^b, while the section 10^b is also provided with a flange 13 at its lower end corresponding with a similar flange 14 on the lower section 10^c. These flanges are 70 respectively connected together in any suitable manner, as by bolts or otherwise, and preferably have arranged between them suitable packing so as to provide for fluid-tight connections.

Within the section 10^a is located a bearing sleeve 15 having at its lower end an annular laterally extending flange 16 fitting between the flanges 11 and 12 and separating the annular compartment 17 in the section 10^a from 85 the compartment 18 in the section 10^b. At the upper end of this sleeve 15 I secure thereto a suitable packing gland 19 and fitted within this gland is a tubular shaft 20 which projects through a bearing sleeve 21 in the section 10^c which also carries a packing gland 22 similar to the gland 19, said bearing sleeves 15 and 21 being provided with removable wear collars 23 and packing 24, as shown in Figure 2.

The section 10^a, as shown, is spaced a considerable distance from the outside wall of the sleeve 15 while the section 10^c closely fits the shaft 20, thus providing the closed compartment 18 which houses the main worm 90

gear 23 surrounding and secured to the shaft 20, as shown in Figure 2, by stud bolts 49, or in any other suitable manner.

Interposed between the worm gear and the upper end of the section 10^a are suitable thrust bearings 24, while similar bearings 25 are interposed between the upper end of the worm gear and the flange 16. These bearings may be of the ball type or of the roller type and both sets, as well as the worm, preferably operate in a bath of heavy oil or similar lubricant.

Secured to one side of the section 10^b is a housing 26 which extends laterally of the casting, as particularly shown in Figures 3 and 4, where it has formed integrally therewith a motor housing 27. This motor housing has journalled therein any suitable type of rotor 28, mounted upon a shaft 29 which is journalled in bearings at the outer end of the motor housing 27, at the end of the housing 26 adjoining the motor housing and at the opposite end of said housing 26, the bearings being indicated respectively at 30, 31 and 32. As shown in Figure 3, I preferably make the motor housing of two sections, which may be joined together in any suitable manner, and attach the inner half of the motor housing to the housing 26 by lag screws 33, and provide in the inner half of the motor housing a discharge chamber 34 which communicates with the annular chamber 17 through a discharge pipe 35, as shown in Figure 1. The drive shaft 29 of the motor, therefore, extends through the chamber 34 and bearing 31 into a chamber 36 in the housing 26 and there carries a worm 37 which meshes with the worm gear 23 on the tubular shaft 20.

I preferably provide a packing gland 38 to prevent leakage of oil or other lubricant from the chamber 36 into the discharge chamber 34 and also to prevent ingress of water into the chamber 36. I also have shown the worm provided with a thrust bearing 39 arranged between said worm and the bearing 32 so as to take any end thrust on the shaft 29.

The upper end of the tubular shaft 20 is shown provided with a discharge nozzle having gradually tapering walls so as to produce a restricted exit or discharge orifice of somewhat smaller diameter than the discharge orifice of the section 10^a. The discharge nozzle is indicated at 40 and the discharge opening of the section 10^a is indicated at 41. The relation of these two parts is such that an annular attenuated passage 42 of gradually diminishing size is produced so that the fluid discharged from the pipe 36 under pressure into the chamber 17 in a large volume has its volume considerably decreased at its point of exit, but its speed materially increased, so as to produce an action corresponding to that of a Venturi tube and suck the excavated material through the restricted throat 43 of the discharge nozzle 40 into the

discharge pipe 44 of increasing cross-sectional area, which is preferably removably secured to the upper end of the section 10^a by means of bolts 49, as shown.

Secured to the lower end of the tubular shaft 20 is a collar 45, see Figure 1, having one or more cutter blades 46 secured thereto which revolve with the tubular shaft and loosen the material being operated upon. These blades are, as shown, constructed with a suitable pitch so as to throw the material inwardly toward the receiving end of the tube and thus place the material in position to be acted upon by the suction produced by the ejector action.

If desirable, the discharge tube 44 may be provided with a valve section 50, as shown in Figure 6, so that in the event of the tube 20 becoming clogged with roots or other material incapable of passing the restricted throat 43, the gate valve in section 50 can be closed and all of the water discharged from the motor and annular discharge opening 41 into discharge pipe 44 will be forced downwardly through throat 43 into nozzle 40 and the tube 20, and thus effectively dislodge and discharge from the lower end of said tube 20 all such material.

While I have designed this device especially for under-water excavation, such as is required in open caissons for bridge piers and the like, I wish it to be understood that the device is capable of use in hydraulic dredging of all kinds and can be effectively employed in dry sand or gravel excavating where there is sufficient water to discharge into the pit for liquefying the material.

In the operation of the device, as thus disclosed, water under pressure is forced into inlet of the motor and impinging against the blades of the rotor 28, drives the shaft 29 and through the worm 37 and worm gear 23 the tubular shaft 20 is rotated, thus causing the cutters 46 at its lower end to loosen the material and draw the same inwardly toward the inlet of the rotating tube 20. After driving the motor, the water is discharged into the chamber 34 and through the discharge pipe 35 into the annular compartment 17, where it is, as before stated, discharged through the restricted passage 42 into the discharge pipe 44 at an extremely rapid rate of speed, thus producing an ejector action and drawing the material loosened by the blades 46 up through the tube 20 where it mingles with the water from the chamber 17, and is discharged through the pipe 44 at any suitable point.

It will be noted that the chamber 18 is effectively separated from the chamber 17 and also from the chamber 34 so that the gearing necessary to drive the tube, namely, the worm 37 and worm gear 23, are effectively isolated from the material being handled and from the water used for power. It will also

be noted that none of the material being handled comes into contact with the collars 47 of the bearings of the tube 20 and the shaft 29 is also protected from anything but clean water which passes from the discharge of the motor through the chamber 34 and into the pipe 35. Thus, all of the parts are effectively protected against wear, with, of course, the exception of the nozzle 40 and tubular shaft 20, which I preferably make of special wear-resisting metal and secure to the tube 20 in such manner that it may be readily removed and replaced at low cost.

It will be readily seen that a situation may arise when it might be desirable not to use the water driving the motor 27 to rotate the suction tube or shaft 20 in series but have independent water connections to the ejector and motor, as shown, for example, in Figures 7 and 8, in which a pipe 51 supplies water under pressure to a Y-connection 52 having one branch 53 provided with a valve 54 communicating with and controlling supply to the motor 27, as shown. The other outlet of the Y-connection 52 communicates with a second Y-connection 55, which is in communication by means of the branch pipe 56 with the annular chamber or compartment 17 surrounding the discharge nozzle 40 of the suction tube of shaft 20 of the ejector. The other outlet or branch of the Y-connection 55 is in communication with another Y-connection 57 having one of its outlets in communication by means of the branch pipe 56' with the discharge of the motor 27, while the other and lower outlet of the Y-connection 57 is in communication with a downwardly extending discharge pipe 58, which may lead to the excavation or body of water being dredged. Interposed between the Y-connections 52, 55 and 57 and discharge pipe 58 are provided valves 59, 60 and 61, as clearly shown in Figure 6, which will permit the flow and path of the water supply under pressure entering into pipe 51 to be diverted, as follows:

If the valves 59 and 61 are closed and valves 54 and 60 are open, the water supply under pressure will pass through the branch pipe 53, through the motor 27 and operate the same and rotate suction tube 20, and the discharge water of said motor 27 will pass by means of branch pipe 56', connection 57, valve 60, connection 55 and branch pipe 56 into the compartment or annular chamber 17 surrounding the nozzle 40 and operate the pump or excavator, as heretofore described.

If the valves 54, 59, and 61 are open and valve 60 is closed, the motor 27 will rotate the discharge or suction tube 20, as heretofore explained, and the discharge water from the motor will pass through the pipe 58 to the bottom of the excavation, while the ejector or compartment or annular chamber 17 surrounding the rotating nozzle 40 will receive a supply of water under pressure di-

rectly from the supply pipe 51, as will be clearly understood and needs no further explanation.

If the valve 50 in discharge pipe 44 and valves 54 and 60 are closed and valve 59 is opened, a direct supply of water under pressure can be made to enter into the annular chamber 17 and any obstructions in the suction tube 20 can be blown out, as will be readily understood.

In Figures 9 and 10 are shown a similar arrangement of piping and valves for removing obstructions in the discharge pipe of a dredge of the type as shown, for example, in former U. S. Patent No. 80,225, to James Robertson, dated July 21, 1868, in which 63 represents the float or scow, 64 the discharge pipe having its lower or inlet end 65 properly supported in the bottom of the river by suitable rigging 66, as is common in this class of devices. 67 is the pipe which supplies the supply of water under pressure into the lower end of the ejector 74 attached to and at bottom of said discharge pipe 64, said ejector being preferably of the Venturi type, as shown, and needs no further disclosure.

Said discharge pipe 64 and water pressure supply pipe 67 are put in communication with each other at their upper sections by means of a branch pipe 68, said pipes 64, 67 and 68 being interconnected by Y-connections 69 and 70 and provided with controlling valves 71, 72 and 73 arranged with respect to each other in said pipes 64 and 67 and disposed as to the connection of the Y-connections 69 and 70, as shown, so that if valves 71 and 73 are open and valve 72 is closed, the water supply under pressure in pipe 67 will flow to the lower or inlet end of the ejector 74, and in so doing draw into the lower end 65 of the discharge pipe 64 any loose material which may be adjacent to said end, and force the same to be entrained and lifted by the upward movement of said water in said pipe 64 and discharged and deposited in said scow 63, which operations are well known and need no further explanation.

Should any material be drawn into and be lodged in the lower end 65 of the discharge pipe 64 or the ejector 74, the valves 71 and 73 are closed and the valve 72 opened, when the water under pressure is permitted to flow from the water supply pipe 67 into pipe 68 and down the discharge pipe 64 and exert a pressure on any obstructing débris in said pipe 64 and ejector 74 and quickly and efficiently blow the same out through the opening at the lower end 65 and thoroughly clean out the cooperating passages in said pipe 64 and ejector 74.

By closing the valve 72 and opening the valves 71 and 73, the dredging operations can be resumed without in any way disturbing the adjusted positions or requiring to be

dismantled any of the cooperating parts of the dredge.

What I claim is:

1. In an excavating machine, a casing, means for dividing the casing into compartments, driving mechanism including gearing arranged within one of the compartments, a rotatable suction tube extending through said compartments and connected to said gearing, and means for discharging a power fluid into the other of said compartments and discharging the same therefrom, said discharged fluid producing a rarefaction in the rotatable suction tube to draw material into said tube and discharge the same therefrom. 70 75
2. In an excavating machine, a casing, means dividing said casing into separate compartments, a fluid motor carried by the casing, a rotatable suction tube extending through said compartments, gearing from the motor to said tube for rotatably driving the latter, said gearing arranged in one of said compartments, and a discharge from the motor leading to the other of said compartments and arranged to discharge therefrom and produce rarefaction within said tube. 80 85
3. In an excavating machine, a casing, a rotatable suction tube passing through said casing and having a reduced end arranged within the discharge orifice of the casing, a fluid motor for rotating said tube, means operating in the rotation of said tube for loosening the material to be operated on and drawing the same toward the axis of the tube, and means for forcing a fluid out of the discharge orifice of the casing and around said tube to produce a rarefaction within said tube. 90 95
4. In an excavating machine, a casing, a partition dividing said casing into separate compartments, packing and bearing elements carried by the partition and casing, a rotatable tube passing through said packing and bearing elements and through said partition, said casing having a discharge aperture, a reduced end of said tube arranged within but spaced from the walls of said discharge aperture, a fluid motor carried by said casing, gearing connecting the motor with said tube at one side of said partition, and a discharge from said motor leading into the casing on the opposite side of said partition and arranged to pass through an annular discharge aperture around said rotatable tube to produce rarefaction therein. 100 105 110
5. In an excavating machine, a casing, a partition dividing said casing into separate compartments, packing and bearing elements carried by the partition and casing, a rotatable tube passing through said packing and bearing elements and through said partition, said casing having a discharge aperture, a reduced end on said tube arranged within but spaced from the walls of said discharge aperture, a fluid motor carried by said casing, 115 120 125 130
- gearing connecting the motor with said tube at one side of said partition, a discharge from said motor leading into the casing on the opposite side of said partition and arranged to pass through the discharge aperture around said tube to produce rarefaction therein, and a cutter blade carried by and rotating with said tube and constructed to loosen the material being operated upon and draw the same toward the axis of said tube. 70 75
6. In an excavating machine, a casing, a suction tube rotatably mounted in said casing, a fluid motor connected to rotate said tube, a source of motive fluid, means for diverting and controlling a portion of said motive fluid for driving said motor and sucking material into and discharging the same from said rotatable tube, independent means for diverting and cutting off another portion of said motive fluid to suck material into and discharge the same from said rotatable tube independent of the motor, and means for cutting off the supply and discharge of motive fluid. 80 85
7. In an excavating machine, a casing, a suction tube rotatably mounted in said casing and provided at its inlet end with cutters, a fluid motor connected to rotate said tube, a source of motive fluid, means for diverting and controlling a portion of said motive fluid for driving said motor and sucking material into and discharging the same from said rotatable tube, independent means for diverting and cutting off another portion of said motive fluid to suck material into and discharge the same from said rotatable tube independent of the motor, and means for cutting off the supply and discharge of motive fluid. 90 95
8. In an excavating machine, a casing, a suction tube rotatably mounted in said casing, and provided with cutters at its inlet end, a fluid motor connected to rotate said tube, a source of motive fluid, means for diverting a portion of said motive fluid for driving said motor, and independent means for diverting another portion of said motive fluid to suck material into and discharge the same from said rotatable tube. 100 105 110
9. In an excavating machine, a suction tube having an inlet and a discharge, an ejector cooperating with said suction tube for sucking material into and conveying the same through the discharge of said tube, a pipe for conveying fluid pressure to operate said ejector, a branch pipe interconnecting said fluid pressure pipe and suction tube, valves arranged and disposed in said suction tube and pipe for conveying fluid pressure to the ejector with respect to said branch pipe interconnections between said fluid pressure pipe and suction tube, to enable when said valves are opened or closed in certain predetermined order to either supply fluid pressure to the ejector and through outlet of said suction tube for the normal operations of the 115 120 125 130

excavator, or cease the operation of the ejector by shunting the supply of fluid pressure into and out through the inlet of said suction tube to dislodge and remove any obstructions

5 lodged within said suction tube.

10. In an excavating machine, comprising a fixed discharge pipe having its inlet end provided with a passage of increasing cross-sectional area, a hollow casing having its outer
- 10 let end detachably connected to the inlet end and communicating with said passage of said discharge pipe, a suction tube rotatably mounted in said casing and having its discharge end in proximity to said hollow cas-
- 15 ing outlet and inlet end of said discharge pipe, a fluid motor connected to rotate said suction tube, and means whereby the fluid for driving said motor is conveyed within said casing and around said suction tube and
- 20 utilized to suck material into and discharge the same from said rotatable tube into the inlet end and passage of said fixed discharge pipe.

25 In testimony whereof, I hereunto affix my
signature.

ANDREW M. LOCKETT.
